Primary Examiner — Jeffrey D Asch*Assistant Examiner* — Tracey J Bell(74) *Attorney, Agent, or Firm* — Skaar Ulbrich Macari, P.A.(57) **CLAIM**

The ornamental design for a glove, as shown and described.

DESCRIPTION

FIG. 1 is a top perspective view of our glove.

FIG. 2 is a top plan view thereof.

FIG. 3 is a bottom plan view thereof.

FIG. 4 is a side elevation view thereof.

FIG. 5 is a side elevation view thereof; and,

FIG. 6 is a front perspective view thereof.

The dashed lines indicate stitching features of the glove design. The broken lines outside the perimeter of the glove in the drawings illustrate environmental features and form no part of the claimed design.
